FUSE MECHANISM FOR PROJECTILES

André Varaud, Geneva, Switzerland

Application April 20, 1933, Serial No. 667,118
In Switzerland April 30, 1932

1 Claim. (Cl. 102—36)

The present invention relates to fuses for artillery projectiles of the type in which the motive power operating the percussor release mechanism is effected by centrifugal force produced by the 5 rotation of the projectile.

It is known that in such fuses, the motive power is an essentially variable quantity, as the centrifugal force varies with the speed of rotation of the projectile and with the distance of the 10 weights from the center. In the known constructions the weights operating the driving member of the release mechanism of the percussor are arranged on toothed sectors which they set in motion by moving away from the axis of the fuse 15 in course of working. The strain which they exert on the toothed sector, that is to say on the mechanism altogether, is therefore considerably greater at the end of the course of the said weights than at the commencement.

It has been attempted to compensate these 20 differences by means of regulator mechanism, but the latter has proved insufficient and it has been attempted to make up for this insufficiency by reducing the length of the path of the centrifugal 25 weights, for instance by inserting demultiplication gearing between the toothed sector and the members driven thereby. This latter means has also proved precarious in view of the principle of the regulator mechanism employed in fuses of the 30 described type.

The primary object of the present invention is to remedy these defects by combining with the 35 centrifugal sector or sectors a regulator device with repose escapement having the axis of the balance arm and of the escapement wheel perpendicular to each other and in which each rest is determined by the contact of the point of a tooth of the escapement wheel with a circular bearing, integral with the axle of the balance arm.

The single figure of the drawing is a partial 40 section in elevation of a fragment of a fuse, the section being taken through the longitudinal axis thereof.

As clearly shown in the drawing, the cylindrical case 1 of the fuse mechanism contains in its 45 interior at 2 and 3 two centrifugal members composed of cylindrical pistons movable outwardly from the center. By means of racks 3a these members transmit the motive power produced by 50 the action of centrifugal force thereon to the pinion 4 of the central shaft 5. From pinion 4 the force is transmitted through the toothed wheel 6 and a satellite pinion of the latter, not shown in the drawing as it is situated behind this 55 wheel, to the escapement at the upper part of the

mechanism. As shown, the axle 8 of the escapement wheel 7 is perpendicular to the axle 9 of the balance arm 10.

With this construction, each rest is determined by contact of the point of a tooth of the escapement wheel 7 with a member integral with the axle 9 of the balance arm 10.

Such a regulator device possesses the peculiarity of not being affected by the variations of the motive power generated by centrifugal force, 65 the indispensable iso-chronism of the oscillations of the balance arm for effecting a sufficiently exact regulation of the working of the fuse mechanism being obtained by the fact that the balance arm has oscillations of great amplitude. 70

This type of regulator has long ago been abandoned in clock-making, because it wears out too quickly and only works for a short time in good condition. This feature, however, is not objectionable in the case of a fuse intended to work 75 only for a few seconds during which such regulator integrally preserves all its qualities.

What I claim as my invention and desire to secure by Letters Patent of the United States is:—

In fuse mechanism for projectiles of the character described a cylindrical casing, two centrifugally operated slideable members mounted in said casing movable outwardly from the axis of said casing, a shaft axially mounted in said casing, means whereby the movement of said slideable members imparts rotary movement to said shaft, a balance arm, an axle for said arm mounted axially in said casing, regulator mechanism in said casing, an escapement wheel appertaining to said regulator mechanism, an axle for said 85 wheel, this axle being situated at a right angle to said axle for said balance, and means transmitting the force from said shaft to said escapement mechanism. 85
